Claims priority, application Switzerland Sept. 19, 1958
7 Claims. (Cl. 101—3)

The present invention relates to presses for working material such as, for instance, paper and cardboard sheets, and more particularly to presses for submitting said sheets to embossing operations.

Such presses generally allow embossing from the very moment they are capable of providing the high pressures required by this kind of work. However, the exerted pressure is not the sole factor which is important when quality embossing is desired, the time for which the pressure is applied playing a large part in determining quality. For this reason, the working rate should, for example, be lowered when passing from cutting operations which are fast to embossing operations. In a press cutting, for instance, 4000 sheets per hour, it is not uncommon to be compelled to slow down the speed to 600 cycles/hour for embossing.

In order to increase production, a press according to the invention comprises at least two possible working rates, the speed of one of them is a fraction of the other, and means are provided making it possible to change automatically from one to the other in the course of each working cycle, so that the slowest rate is employed during at least part of the active period of each cycle and the fastest rate at other times.

During the active period of each cycle is effected the setting under pressure of the tools, the conveying of sheets from registering and take-in stations to processing and waste or deposit stations.

The attached drawing shows an embodiment of the invention given by way of example. In the drawing:

FIG. 1 is a longitudinal cross-section of a press of the type under consideration, showing the main elements necessary for a better understanding of the invention.

FIG. 2 is a longitudinal cross-section of the driving members making it possible to transmit to said press the contemplated running rates.

FIG. 3 is a diagram explaining the running of the press when effecting embossing.

FIG. 4, finally, is a schematic electrical diagram of the control means for the press to govern the driving members of FIG. 2.

The press represented in FIG. 1 comprises a pair of frames, one of which is seen at 1, these frames supporting an upper fixed plate 2 and a support 3 for the driving mechanism of a movable lower plate 4.

Plate 4 goes up and down successively once during each working cycle of the press, and is driven by toggle levers 5, operated by connecting rods 6 which are coupled to main shaft 7 by eccentrics. A motor (not shown) drives a flywheel 8, and shaft 9 and worm 10. Worm 10 meshes with a cogwheel 11 keyed on the main shaft 7 to drive the latter. On either side of the press is an endless chain 12, these chains being connected by conveying gripping bars 13 and impelled by an intermittent translatory motion.

To a small plate 14 are fed the paper or cardboard sheets to be worked. These sheets are registered by known means (not shown) and are seized by the gripping bar located immediately under the chain wheels 15, then conveyed one by one between the plates 2 and 4. Then, under the action of the toggle-levers, the plates, bearing appropriate tools and counter-tools, are applied one against the other and perform the desired cutting or em-

2

bossing operation, or perhaps these two operations at one and the same time.

Said operations are repeated each operating cycle, corresponding to one revolution of the main shaft 7.

5 In the press described above, the running speed is uniform and will be, for instance, 4000 cycles/hour for rule cutting which should be reduced to 600 cycles/hour for embossing operations. These speeds can be obtained, for instance, by means of an appropriate speed changing device by varying the motor speed.

10 As already stated above, there results from the application of these two working speeds a very low output which may be, for instance, nearly seven times inferior to the possible maximum output of the press.

15 Now, the reduced speed required by the embossing operations serves only to increase the duration of setting the plates under pressure and it is not necessary to reduce in the same ratio the conveying speed of the sheets.

20 In the case of the press described, the setting under pressure of the plates is substantially achieved in 60° of rotation of the main shaft 7, and hence during one sixth of each cycle, of which five sixths are otherwise employed. Therefore, the ideal would be to make it pos-

25 sible for the main shaft to perform during each cycle a rotation of 300° at 4000 r.p.h., followed by a rotation of 60° at 600 r.p.h. Thus, the maximum theoretical output of the press would be obtained which would amount to a production of 3433 worked sheets an hour.

30 However, it is mechanically difficult to realize this ideal case because of the stresses involved and of the masses in motion.

Nevertheless, it is possible to try to come close to it, for instance according to the example which will follow, 35 where the press is arranged so as to be in a position, in the course of each cycle, to work at two successively different rates, one of which is four times faster than the other, it being understood that other ratios comprised between three and seven still present some sufficiently practical interest.

40 The slowest rate in the following will be at 600 operations per hour, as indicated above in the given case of embossing, the fastest will be at 2400 cycles per hour and the obtained working average will be substantially 45 1800 cycles per hour, corresponding to an output of nearly half of the possible maximum output of 4000 cycles/hour.

To come to this result, a speed changing mechanism with two translation ratios such as shown in cross-section 50 in FIG. 2 will be placed on the shaft 9 between the flywheel 8 and the worm 10.

The flywheel 8, turning idle on the shaft 9 is integral with a toothed wheel 16 and a disk 17 of a magnetic coupling, whose other disk 16 is keyed on the shaft 9.

55 The toothed wheel 16 meshes with wheel 19 fixed to wheel 20 engaging wheel 21 located on the shaft 9 and turning idle on this latter. The number of teeth of the cogwheels are such that there be between the wheel 16 integral with the flywheel 8 and the wheel 21, a step down ratio of four to one.

60 Finally, the toothed wheel 21 is fixed to disk 22 of a magnetic coupling, the other disk 23 of which is keyed to the shaft 9.

Elements 24 and 25 schematically represent the excitation coil operating on the magnetic coupling elements 17—18 and 22—23 with a view of setting them into action.

65 It is evident that a coupling of elements 17—18 will join flywheel 8 directly as with the shaft 9 and to impart the speed of the flywheel to this shaft. A coupling of elements 22—23 joins the flywheel 8 to the shaft 9 through the gears 16—19—20—21, and will cause the shaft speed

to be slowed down to one fourth of that of the flywheel. Therefore, if this latter turns so as to transmit to the main shaft 7 of the press of FIG. 1, a speed of 2400 r.p.h., when the coupling 17-18 is operating, this speed will be slowed down to 600 r.p.h., when the coupling 22-23 is operative.

The alternating excitation of the coils of both couplings can be produced by contacts operated by the main shaft of the press so as to actuate the coupling 17-18 during 300° of rotation and the coupling 22-23 during the remaining 60°.

Practically, this is impossible due to the shocks to which the described mechanism would be submitted by passing so suddenly from one speed rate to the other.

The diagram of the FIG. 3 shows a practical working example of the presses of FIG. 1 equipped with the gear-changing system of FIG. 2.

The abscissas correspond to a press working cycle, i.e. to a rotation of 360° of the main shaft 7, or of any other shaft performing a one turn working cycle. The ordinates correspond to the speed of the shaft.

The centre abscissas is zero, which is supposed to occupy the middle of the period of setting under pressure of the plates which period extends therefore from 330° to 30°, with a corresponding working speed of 600 cycles/hour. The corresponding part of the diagram is hatched.

The coupling 17-18 being assumed to have been actuated and the shaft 7 turning normally at 2400 r.p.h. is the case at the 180° indication, which is the beginning of the curve shown.

At 210°, the coupling 17-18 is disengaged, the press continuing however to work by virtue of the acquired inertia. However, the flywheel 8 no longer intervenes, for it now turns freely on the shaft 9, at the uniform speed which is imparted to it by the motor. This occurs at point A of the curve.

The speed of the elements in motion decreases, but before it drops to 600 r.p.h., at point B corresponding to 296°, the disks 22-23 are engaged. This operation corresponds to setting the press at the rate of 600 cycles/hour. The coupling will first exert a slight braking on the system, but shortly before the time position corresponding to 330°, the desired rate of 600 r.p.h. will have been achieved. By applying motive power, it will be maintained up to point C, located at 3° beyond zero or the upper dead position of the movable plate. At this point, the coupling 22-23 is disengaged and the press is again left to itself. This will maintain the acquired reduced speed since the dead point being overrun, the pressure operating on the lower plate and which will be for instance of several hundred tons, will tend to protract the motion of the toggle levers and members which drive them.

Shortly before the end of the setting under pressure, at point D located at 28°, the coupling 17-18 is set again into action; that is to say the press will be driven at 2400 cycles/hour. In this case also, there will be a slight sliding between elements 17 and 18 with, however, a rapid acceleration up to about 80°, where the high rate will be restored and maintained up to point A, or 210°. The operations already described then start again and repeat as long as desired.

It is evident that the clutching and declutching angles of the two couplings such as indicated above are not limitative, other angles being likely to provide excellent results.

The diagram of FIG. 4 gives an example of coupling control for the main shaft 7 and an arrow indicates its supposed turning direction in this figure.

The coil 24 represents the coils 24 of FIG. 2, controlling the fast rate and the coil 25 the coils governing the slow rate of the press.

On the shaft 7 are wedged two cams 26 and 27 operating two switches 28 and 29 placed in a low voltage control circuit having supply terminals 30, each of these switches exciting a coil 31 or 32, on which depends the

position of a member 33 or 34. These commutators operate a high voltage circuit fed by terminals 35 and supplying excitation current to the coils 24 and 25.

In the condition represented, the system is at point B of the curve of FIG. 3, i.e. at the moment of initiating the slow running rate.

The cam 27 closes the switch 29, and by the resulting excitation of the coil 32, the armature of the commutator 34 is raised. With the commutator 33 at rest, the feeding circuit of coil 25 by elements 36, 37 and 38 is opened. It has been seen that the coil 25 operates the coupling 22-23, on which depends the slow running rate of 600 r.p.h., given by way of example.

The shaft continues to turn, and the cam 27 thus ultimately causes the switch 29 to open after having covered an angle of 67°. This is the point C of the curve of FIG. 3, i.e. of declutching of the slow running rate. The opening of the switch 29 causes the armature 34 to fall and to open the circuit of the coil 25.

The cam 26 turns jointly with the cam 27 and after having covered an angle of 92° from the illustrated starting position, it will cause the switch 28 to be closed, while 29 is still open.

The excitation of the coil 31 resulting therefrom causes the armature 33 to be raised. The lower bar of armature 33 breaks a circuit including elements 39, 40, 34, 41, 24 and 42. The coil 24, being excited, sets the coupling 17-18 into action, i.e. the fast running rate of the press corresponding to point D of the curve of FIG. 3.

The closing period of the switch 28, extending over 182° of rotation of the cam 26, the fast running will be maintained until it reaches that point corresponding to A on the curve of FIG. 3.

At that moment, the fast speed driving, i.e. 2400 r.p.h., is interrupted and the two switches 28 and 29 remain open during still 86° until they reach the illustrated starting position, i.e. the re-clutching of the slow running rate.

Therefore, the passage at the desired moment, from one running rate to the other and inversely, takes place automatically in the course of each working cycle of the press in relation with the rotation of its main shaft 7.

However, this is possible only in the represented position of FIG. 4 of the commutator 43, allowing the feeding of the switches 28 and 29.

In its two other positions, it disconnects these switches and sets the described contrivance out of gear.

In its median position, it is seen that the coil 31 is excited through the conductor 44, thus raising its armature so as to make the commutator 33 occupy the feeding position of the fast running coupling coil 24. This feeding is possible owing to the fact that the commutator 34 occupies at that moment its resting position inverse to that represented in the drawing. The press is therefore in a state of fast running.

If now the commutator 43 is brought into its third position which connects it to the conductor 45, there results the setting under voltage of the coil 46 via line 47, the armature 48 breaking the feeding circuit of the coil 49 operating a brake (not shown).

The press equipped with the change-gear of FIG. 2 governed by a circuit such as that of FIG. 4 will be able to work selectively as a normal press or as a special press at two successive running rates or may be immobilized in any desired position, this by the simple control of the switch 43.

What is claimed is:

1. Apparatus comprising a sheet embossing press including at least one reciprocable member, a conveyor system for conveying sheets to said press, and means for driving said system and press at different speeds; said means comprising a shaft coupled to said member and system to drive the same, and a control for said shaft comprising means operatively coupled to said shaft to rotate the same at one speed before said reciprocating member is brought to its range of operative positions and

at the other speed before the reciprocating member leaves the range of operative positions.

2. In combination with a sheet embossing press including at least one reciprocable member and a conveyor system for conveying sheets to said press, means for driving said system and press at different speeds and comprising a shaft, said reciprocable member having a range of operative positions corresponding to a determinable angle of rotational movement of said shaft, a flywheel freely rotatable on said shaft, means to drive said flywheel, clutch discs concentric with and freely rotatable on said shaft, one of said discs being fixed to said flywheel and the other being separate therefrom, two further clutch discs concentric with and keyed to said shaft, said further discs being operatively disposed with respect to and adapted for respectively engaging the first said discs in pairs, control means operatively associated with said discs to control engagement of the same, and a gear train coupling said other of the first said discs to said flywheel whereby the speed of said shaft is controllable in accordance with the selective engagement of said further discs by the first said discs; said control means being operatively coupled to said shaft to engage one of the pairs of discs at a time, said control means engaging the pair of discs associated with the gear train before said reciprocating member is brought to its range of operative positions and the other pair of discs being actuated before the reciprocating member leaves the range of operative positions.

3. A device comprising a sheet embossing apparatus including at least one reciprocable member, a conveyor system for conveying sheets to said press, and means for driving said system and apparatus at different speeds whereby embossing and conveying operations are efficiently effected; said means comprising a shaft coupled to said member and system, a flywheel freely rotatable on said shaft, means to drive said flywheel, magnetic discs concentric with and freely rotatable on said shaft, one of said discs being fixed to said flywheel and the other being separate therefrom, two further magnetic discs concentric with and keyed to said shaft, said further discs being operatively disposed with respect to and adapted for respectively engaging the first said discs, inductance coils adjacent said discs to control a magnetic engagement of the same, a gear train coupling said other of the first said discs to said flywheel whereby the speed of said shaft is controllable in accordance with the selective engagement of said further discs by the first said discs, and a control for said coils; said control comprising a power source, first and second relays each including a relay coil, an armature and first and second sets of contacts, the first sets of contacts being connected in electrical series between said power source and one of the first said coils, the second sets of contacts being connected in electrical series between said power source and the other of the first said coils, first and second switches connecting the relay coils to the power source, and first and second cam means coupled to said shaft and adapted to operate said switches whereby the first said coils are effectively connected to said power source, said cam means being operatively disposed on said shaft to actuate one of the first said coils at a time with an interruption between actuation of these coils, said cam means actuating the coil associated with the gear train before said reciprocating member is brought to a range of operative positions corresponding to a determinable angle of rotation of said shaft and the other coil being actuated before the reciprocating member leaves said range of operative positions.

4. A sheet embossing press comprising first and second movable sections, and means for driving said sections at different speeds; said means comprising a drive operatively coupled to and adapted for driving said first section, means operatively coupled to and adapted for driving said second section, a main shaft coupled to said drive and second said means to drive the same, said second section having a range of operative positions correspond-

ing to a determinable angle of rotational movement of said main shaft, a further shaft coupled to said main shaft, a flywheel freely rotatable on said further shaft, means to drive said flywheel, clutch sections on said further shaft, one of said clutch sections being fixed to said flywheel and the other being separate therefrom, two further clutch sections keyed to said further shaft, said further clutch sections being operatively disposed with respect to and adapted for respectively engaging the first said clutch sections, control means adjacent said clutch sections to control engagement of the same in pair, a gear train coupling said other of the first said clutch sections to said flywheel whereby the speed of said shafts is controllable in accordance with the selective engagement of said clutch sections; said control means comprising means operatively coupled to said main shaft to engage one of the pairs of clutch sections at a time with an interruption between engagement of these pairs, the clutch section pair associated with the gear train being engaged before said reciprocating member is brought to its range of operative positions and the other clutch section pair being engaged before the reciprocating member leaves the range of operative positions.

5. In an apparatus comprising a sheet embossing press including at least one reciprocable member and a conveyor system for conveying sheets to said press, means for driving said system and press at different speeds, said means comprising a conveyor system drive operatively coupled to and adapted for driving said conveyor system, a linkage means operatively coupled to and adapted for driving said reciprocable member, a main shaft coupled to said drive and linkage means to drive the same, said reciprocable member having a range of operative positions corresponding to a determinable angle of rotational movement of said main shaft, a further shaft, means coupling said shafts, a flywheel freely rotatable on said further shaft, means to drive said flywheel, discs rotatable on said further shaft, one of said discs being fixed to said flywheel and the other being separate therefrom, two further discs keyed to said further shaft, said further discs being operatively disposed with respect to and adapted for respectively engaging the first said discs in pairs, means adjacent said discs to control engagement of the same, a gear train coupling said other of the first said discs to said flywheel whereby the speed of said shafts is controllable in accordance with the selective engagement of said further discs and the first said discs, and a control for the means controlling engagement of the discs; said control comprising means operatively coupled to said main shaft to engage one of the pairs of said discs at a time with an interruption between sequential engagements, the pair of discs associated with the gear train being engaged before said reciprocating member is brought to its range of operative positions and the other pair of discs being engaged before the reciprocating member leaves the range of operative positions.

6. Apparatus comprising a sheet embossing press including at least one reciprocable member, a conveyor system for conveying sheets to said press, and means for driving said system and press at different speeds whereby embossing and conveying operations are efficiently effected; said means comprising a conveyor system drive operatively coupled to and adapted for driving said conveyor system, a toggle linkage means operatively coupled to and adapted for driving said reciprocable member, a main shaft coupled to said drive and linkage means to drive the same, said reciprocable member having a range of operative positions corresponding to a determinable angle of rotational movement of said main shaft, a further shaft, a worm and gear combination coupling said shafts, a flywheel freely rotatable on said further shaft, means to drive said flywheel, magnetic discs concentric with and freely rotatable on said further shaft, one of said discs being fixed to said flywheel and the other being

separate therefrom, two further magnetic discs concentric with and keyed to said further shaft, said further discs being operatively disposed with respect to and adapted for respectively engaging the first said discs, inductance coils adjacent said discs to control a magnetic engagement of the same, a gear train coupling said other of the first said discs to said flywheel whereby the speed of said shafts is controllable in accordance with the selective engagement of said further discs by the first said discs, and a control for said coils; said control comprising first and second power sources, first and second relays each including a relay coil, an armature and first and second sets of contacts, the first sets of contacts being connected in electrical series between said first power source and one of the first said coils, the second sets of contacts being connected in electrical series between said first power source and the other of the first said coils, first and second switches connecting the relay coils to the second power source, and first and second cam means on said main shaft and adapted to operate said switches whereby the first said coils are effectively connected to said first power source, said cam means being operatively disposed on said main shaft to actuate one of the first said coils at a time with an interruption between actuation of these coils, the coil associated with the gear train being actuated before said reciprocating member is brought to its range of operative positions and the other coil being actuated before the reciprocating member leaves the range of operative positions.

7. For use with a sheet embossing press including at least one reciprocable member, and a conveyor system for conveying sheets to said press; means for driving said system and press at different speeds whereby embossing and conveying operations are efficiently effected; said means comprising a conveyor system drive operatively coupled to and adapted for driving said conveyor system, a toggle linkage means operatively coupled to and adapted for driving said reciprocable member, a main shaft coupled to said drive and linkage means to drive the same, said reciprocable member having a range of operative positions corresponding to a determinable angle of rotational movement of said main shaft, a further shaft, a
